UNITED STATES PATENT OFFICE.

JAMES A. CAMERON, OF BROOKLYN, NEW YORK, AND ROBERT McC. JOHNSTONE, OF ROSELLE PARK, NEW JERSEY, ASSIGNEES TO CAMERON MACHINE COMPANY, OF BROOKLYN, NEW YORK, A CORPORATION OF NEW YORK.

SLITTING MACHINE.

Application filed December 3, 1923. Serial No. 678,338.

To all whom it may concern:

Be it known that JAMES A. CAMERON, a citizen of the United States, and a resident of New York city, in the borough of Brooklyn, county of Kings, and State of New York, and ROBERT McC. JOHNSTONE, a citizen of the United States, and a resident of Roselle Park, in the county of Union and State of New Jersey, have invented certain new and useful Improvements in Slitting Machines, of which the following is a specification.

This invention relates generally to slitting machines for flexible materials and has for its main object and feature the provision of means whereby two groups of slitting elements may be employed in connection with complementary slitting means together with devices whereby one group of slitting elements may be adjusted to produce a different width of section while the other group is cooperating with the complementary slitting means to the end that the slitting operation may be changed from one width to another without breaking the flowing web and without stopping its flow. The broad features of the invention herein disclosed are claimed in application Ser. No. 678,332 filed December 3, 1923. The slitting means employed may of course vary widely and may be either of the score-cut or the shear-cut type, and, if of the shear-cut type, the arrangement may be as disclosed in application Ser. No. 678,334 filed December 3, 1923, and some of the claims herein are intended to cover the disclosure of said application Ser. No. 678,334 filed December 3, 1923, and also to cover some of the features disclosed in application Ser. No. 678,332 filed December 3, 1923.

In the accompanying drawings, the invention is disclosed in a concrete and preferred form in which

Fig. 1 is an end elevation of a machine embodying the invention.

Fig. 1^a is a fragmentary view of a latch that may be employed in connection with the invention.

Fig. 2 is a side-elevation of the machine shown in Fig. 1.

Fig. 3 is a transverse vertical sectional view on the plane of line 3—3 of Fig. 2.

Fig. 4 is a longitudinal vertical sectional view on the plane of line 4—4 of Fig. 1.

Fig. 5 is a diagrammatic view of a slitting

machine associated with a board or paper making machine and a sheeter.

The slitting devices include two sets, one consisting here of slitting means 1 which is a main slitting member or backing roll or a smooth-faced slitting member having a hardened surface in accordance with the well-known Cameron practice, and a group of slitting elements 2 here consisting of score-cutters 2 while the other set of slitting devices consists of member 1 and the group of score-cutters 3. The two or more groups of score-cutters 2 and 3 are mounted on the carrying member 4 which latter is mounted to turn in a suitable support that will hereafter be more particularly described, and are spaced apart circumferentially on the carrying member, being mounted on faces 5 and 6 of the carrying member. It will be understood that, if one group of score-cutters is in engagement or proper position with reference to member 1, the other group may be adjusted by sliding them along the face of the carrying member after which they may be secured in position by means of screws 7. If it is now desired to vary the width of the slitting sections, the carrying member is turned in its bearings to bring said other group of cutters into proper position with respect to member 1 and this can be done without breaking web 8 or interrupting its flow. In addition to the adjustments described, it is preferred to mount the carrying member in a support that can be moved toward and away from member 1; and it is also preferred to have means to slide the carrying member longitudinally of its axis.

As here disclosed these parts take the following form:

9 indicates a framework in which is mounted a support here consisting of two arms 10 and 11. These arms are pivotally supported on center 12. The free ends of the arms are provided with bearings 13 and 14 and in these bearings the carrying member 4 is mounted. Any suitable means may be provided to rock the arms but, preferably, each arm carries a sector 15 or 16 with which engage screws 17 and 18 that can be operated in unison by reason of two pairs of bevel gears 19 and handle 20. Carrying member 4 is provided with a sleeve 21 that carries a gear 22 and with this gear meshes

pinion 23, the center of which is at 12. Handwheel 24 is connected to pinion 23 so that by turning said handwheel, the carrying member may be turned in the bearings 5 of the arms to bring either group of cutters into engagement with member 1. Mounted on one of the arms is a latch 25 that consists of a bolt 25^a spring pressed into one of a 10 number of apertures 26 of the carrying member or extension thereof so that, when the carrying member has been turned to a proper position, it becomes latched in position. To withdraw the bolt, handle 27 is turned and cam face 28 moves bolt upwardly and out of aperture 26. At times, it is 15 desirable to be able to move the carrying member lengthwise to compensate for an uneven feed of material from the board mill or paper making machine. In order to be 20 able to do this, extension or sleeve 21 is in 25 slideable engagement with the carrying member by means of key 29 and carries a threaded stem 30 that engages corresponding threads in the carrying member. By turning handle 31, fast to stem 30, the carrying member is moved lengthwise of its own axis in the bearings of the arms.

In operation the preferred practice is to 30 lower the arms away from member 1 and then to turn the carrying member in its 35 bearings.

In Fig. 5, the slitting machine, designated generally by 32 is shown between board mill or paper making machine 33 and sheeter 34. 35 The web is led from the paper making machine over guide roll 35 and through the slitters and thence to rollers 36 of the sheeter which latter rollers act to pull the web through the slitting machine.

40 The broad idea, disclosed herein, of score-cut slitting means to sever a web into independent longitudinal sections without distorting the sections out of parallelism together with a feeding device to exert an 45 equal pull on all the sections to thereby advance them in parallelism and severing devices to cut the sections substantially at right angles to their longitudinal advance is 50 not claimed in the present application but forms the subject matter of another application filed Nov. 21, 1924, Ser. No. 751,410.

We claim:

55 1. A slitting machine comprising: a carrying member mounted to turn, two groups of slitting elements on said carrying member, said groups being spaced circumferentially on said carrying member, slitting means to coact with said slitting elements to slit a web, and means for turning said 60 carrying member to bring either of said groups into proper position with relation to the slitting means.

65 2. A slitting machine comprising: a carrying member mounted to turn, two groups of score-cutters on said carrying member,

said groups being spaced circumferentially on said carrying member, smooth-faced slitting means to coact with said score-cutters, and means for turning said carrying member to bring either of said groups into proper position with relation to the smooth-faced slitting means.

3. A slitting machine comprising: a carrying member mounted to turn, two groups of slitting elements on said carrying member, said groups being spaced circumferentially on said carrying member, slitting means to coact with said slitting elements to slit a web, means for turning said carrying member to bring either of said groups into proper position with relation to the slitting means, and means for adjusting the position of the slitting elements of one group lengthwise of the machine while the slitting elements of the other group are co-acting with the slitting means.

4. A slitting machine comprising: a carrying member mounted to turn, two groups of score-cutters on said carrying member, said groups being spaced circumferentially on said carrying member, smooth-faced slitting means to coact with said score-cutters, means for turning said carrying member to bring either of said groups into proper position with relation to the smooth-faced slitting means, and means for adjusting the position of the score-cutters of one group lengthwise of the machine while the score-cutters of the other group are co-acting with the smooth-faced slitting means.

5. A slitting machine comprising: a carrying member mounted to turn, two groups of slitting elements on said carrying member, said groups being spaced circumferentially on said carrying member, slitting means to coact with said slitting elements to slit a web, means for turning said carrying member to bring either of said groups into proper position with relation to the slitting means, means for adjusting the individual position of the slitting elements of one group lengthwise of the machine while the slitting elements of the other group are co-acting with the slitting means, and means for adjusting each group of slitting elements as a unit lengthwise of the machine.

6. A slitting machine comprising: a carrying member mounted to turn, two groups of score-cutters on said carrying member, said groups being spaced circumferentially on said carrying member, smooth-faced slitting means to coact with said score-cutters, means for turning said carrying member to bring either of said groups into proper position with relation to the smooth-faced slitting means, means for adjusting the individual position of the score-cutters of one group lengthwise of the machine while the score-cutters of the other group are co-acting with the smooth-faced slitting means,

and means for adjusting each group of score-cutters as a unit lengthwise of the machine.

7. A slitting machine comprising: a carrying member mounted to turn in a support, 5 two groups of slitting elements on said carrying member, said groups being spaced circumferentially on said carrying member, slitting means to co-act with said slitting elements to slit a web, means for turning 10 said carrying member to bring either of said groups into proper position with relation to the slitting means, and a support sustaining the carrying member and movable to bring it toward or away from the 15 slitting means.

8. A slitting machine comprising: a carrying member mounted to turn in a support, two groups of score-cutters on said carrying member, said groups being spaced circumferentially on said carrying member, smooth-faced slitting means to co-act with 20 said score-cutters, means for turning said carrying member to bring either of said groups into proper position with relation to the smooth-faced slitting means, and a support sustaining the carrying member and 25 movable to bring it toward or away from the smooth-faced slitting means.

9. A slitting machine comprising: a carrying member mounted to turn in a support, 30 two groups of slitting elements on said carrying member, said groups being spaced circumferentially on said carrying member, slitting means to co-act with said slitting elements to slit a web, means for turning 35 said carrying member to bring either of said groups into proper position with relation to the slitting means, a pivotally mounted support sustaining the carrying member, 40 and means for turning the support on its pivot to bring the carrying member toward or away from the slitting means.

10. A slitting machine comprising: a carrying member mounted to turn in a support, 45 two groups of score-cutters on said carrying member, said groups being spaced circumferentially on said carrying member, smooth-faced slitting means to co-act with 50 said score-cutters, means for turning said carrying member to bring either of said groups into proper position with relation to the smooth-faced slitting means, a pivotally mounted support sustaining the carrying member, 55 and means for turning the support on its pivot to bring the carrying member toward or away from the slitting means.

11. A slitting machine comprising: a carrying member mounted to turn in a support, two groups of slitting elements on said carrying member, said groups being spaced circumferentially on said carrying member, 60 slitting means to co-act with said slitting elements to slit a web, means for turning said carrying member to bring either of said groups into proper position with relation to

the slitting means, and means for adjusting the position of the slitting elements of one group lengthwise of the machine while the slitting elements of the other group are co-acting with the slitting means. 70

12. A slitting machine comprising: a carrying member mounted to turn in a support, two groups of score-cutters on said carrying member, said groups being spaced circumferentially on said carrying member, 75 smooth-faced slitting means to co-act with said score-cutters, means for turning said carrying member to bring either of said groups into proper position with relation to the smooth-faced slitting means, a support 80 sustaining the carrying member and movable to bring it toward or away from the smooth-faced slitting means, and means for adjusting the position of the score-cutters of one group lengthwise of the machine while 85 the score-cutters of the other group are co-acting with the smooth-faced slitting means.

13. A slitting machine comprising: a carrying member mounted to turn in a support, two groups of slitting elements on said carrying member, said groups being spaced circumferentially on said carrying member, slitting means to co-act with said slitting elements to slit a web, means for turning 90 said carrying member to bring either of said groups into proper position with relation to the slitting means, a support sustaining the carrying member and movable to bring it toward or away from the slitting means, means for adjusting the individual position 95 of the slitting elements of one group lengthwise of the machine while the slitting elements of the other group are co-acting with the slitting means, and means for adjusting each group of slitting elements in unison 100 lengthwise of the machine. 105

14. A slitting machine comprising: a carrying member mounted to turn in a support, two groups of score-cutters on said carrying member, said groups being spaced circumferentially on said carrying member, smooth-faced slitting means to co-act with said score-cutters, means for turning said carrying member to bring either of said groups into proper position with relation to the 110 smooth-faced slitting means, a support sustaining the carrying member and movable to bring it toward or away from the smooth-faced slitting means, means for adjusting the individual position of the score-cutters 115 of one group lengthwise of the machine while the score-cutters of the other group are co-acting with the smooth-faced slitting means, and means for adjusting the individual position of the score-cutters of one group lengthwise of the machine 120 while the score-cutters of the other group are co-acting with the smooth-faced slitting means, and means for adjusting each group of score-cutters as a unit lengthwise of the 125 machine.

15. A slitting machine comprising: a pair of pivotally supported arms, a carrying member rotatably supported in said arms, two groups of slitting elements on said car- 130

member rotatably supported in said arms, two groups of score cutters on said carrying member, said groups being spaced circumferentially on said carrying member, ¹⁵ smooth-faced slitting means to co-act with said score-cutters to slit a web, a gear on the carrying member, a gear, the center of which is coincident with the center of the pivotal support of the arms, to mesh with the gear on the carrying member and to thereby bring either of said groups into proper position with relation to the complementary smooth-faced slitting means, ²⁰ means for swinging the arms on their pivotal support, means for sliding said carrying member lengthwise of its own axis in said arms, means for adjusting the position of the individual score-cutters of one group while the other group is co-acting with the complementary slitting means.

Signed at New York city, in the borough of Brooklyn, county of Kings, and State of New York, this 28 day of November, 1923.

JAMES A. CAMERON.
ROBERT McC. JOHNSTONE.
